UNITED STATES PATENT OFFICE

FERNANDO J. DIBBLE, OF PEABODY, MASSACHUSETTS, ASSIGNOR TO THE
TELEMETER COMPANY, OF NEW YORK.

TELEHERMOMETER.

SPECIFICATION forming part of Letters Patent No. 474,771, dated May 10, 1892.

Application filed January 24, 1889. Serial No. 297,398. (No model.)

To all whom it may concern:

- Be it known that I, FERNANDO J. DIBBLE, of Peabody, county of Essex, State of Massachusetts, have invented an Improvement in 5 Telemeter Systems, of which the following description, in connection with the accompanying drawings, is a specification, like letters and figures on the drawings representing like parts.
- 10 This invention relates to telemeter systems in which variations of temperature, pressure, or other similar changing force or phenomena occurring at one locality or station may be transmitted to another or distant locality or 15 station and there be recorded, my present invention being an improvement upon the telemeter system shown and described in United States Patent No. 327,526, granted to Charles L. Clarke, dated October 6, 1885.
- 20 One feature of my present invention consists in providing the transmitting apparatus with a solid pallet operating the ratchet-wheel which imparts motion to the pointer or index of the said instrument, the said pallet having 25 secured to or forming part of it the armature of the electro-magnets forming part of the said instrument.
- Another feature of my invention consists in a novel arrangement of circuits, as will be 30 described.
- Still another feature of my invention consists in joining together the armatures controlling the shunt-circuits, so that but one shunt-circuit at a time can be closed.
- 35 My invention further consists in providing the receiving apparatus with a solid pallet, and also with a novel circuit-breaker operated by the said pallet when moved in either direction by either of the receiving-magnets.
- 40 My invention also consists in providing the receiving-instrument with a recording-dial inclosed within the case of the said receiving-instrument and located within the indicating-dial of the said receiving-instrument, substantially as will be described.
- 45 The particular features in which my invention consists will be pointed out in the claims at the end of this specification.
- Figure 1 shows in section and elevation the 50 transmitting apparatus employed by me as connected to the case containing a metallic
- thermometer, the latter and its case and the dial of the transmitter being shown in section; Fig. 2, a front elevation of the transmitter shown in Fig. 1, looking toward the left, with 55 the dial, its co-operating pointer, and the gears employed to rotate the latter being omitted, the said gears being indicated by dotted lines; Fig. 3, a bottom or back view of the transmitter shown in Fig. 1 to more clearly show 60 the contact-points at which the electrical circuits are first closed; Fig. 3^a, a detail to be referred to. Fig. 4 is a top or plan view of the receiving and recording instrument. Fig. 5 is a top or plan view of the receiving-instrument with the recording-dial removed and the arm carrying the recording-pen broken off. Fig. 6 is a sectional detail to be referred to; Fig. 7, a detail of the circuit-closer and circuit-breaker carried by the receiving-instrument; Fig. 8, a diagram of circuits, showing one 65 transmitting apparatus and two receiving apparatuses; Fig. 9, a diagram of circuits, showing but one transmitting and one receiving instrument; Fig. 10, a diagram of a modified arrangement of circuits to be referred to; and Fig. 11 a detail, on an enlarged scale, to more 70 clearly show the winker-armature.
- Referring to Fig. 1, the case A, containing the thermometer A', has secured to it a transmitting apparatus A², consisting of a bed-plate a, to which are secured two sets of magnets a' a², the circuits of which are controlled, as herein shown, by the pointer a³, actuated by the expansion and contraction of the metallic thermometer A', caused by changes of 80 temperature in the locality in which the transmitting-instrument is placed. The plate a has pivoted to its rear side a segmental gear a⁴, (see Fig. 3,) in mesh with a pinion a⁵ on the arbor of the ratchet-wheel a⁶, provided with ratchet-teeth, each of which has its sides oppositely inclined at substantially the same angle, so that the said ratchet-wheel may be rotated in opposite directions, as will be described, by the pallets a⁷ a⁸, (see Figs. 2 and 85 3^a,) secured to or forming part of a bar a⁹, pivoted on a shaft or arbor a¹⁰. The segmental arm a⁴ has secured to it a bar a¹², having at its front end, as shown, a block a¹³ of 90 insulating material, the said block having secured to its opposite sides contact-arms a¹⁴.

a^{15} , provided with contact-points $a^{16} a^{17}$, with which co-operate the metallic pointer a^3 . The contact-arm a^{15} is connected by the fine wire a^{18} (see Fig. 3) to a post a^{19} , connected, as by wire a^{20} , (see Fig. 2,) to the magnet a^2 , and the contact-arm a^{14} is connected by the wire a^{22} to the post a^{23} , electrically connected by a wire a^{24} with a magnet a' .

The pallet-bar a^9 has secured to or forming part of it a yoke b , (see Figs. 2 and 3^a), to which are secured the armatures $b' b^2$ of the magnets $a' a^2$, respectively, so that when one magnet, as a' , attracts its armature b' the armature b^2 of the other magnet a^2 will be thrown or moved out of the influence of the said magnet by the said yoke. The yoke b has secured to its opposite ends contact-springs 2 3, (see Fig. 2,) which co-operate with contact-points (shown as screws 4 5) inserted through posts 6 7, herein shown as secured to the case a . The magnets $a' a^2$ are provided with extended pole-pieces $b^3 b^4$, with the sides of which co-operate auxiliary armatures $b^5 b^6$, respectively, (see Fig. 2,) the said auxiliary armatures being hereinafter designated by me as "winker-armatures." The winker-armatures $b^5 b^6$ are preferably connected to the arms of the yoke b^7 , secured to a hub b^8 , fast on a shaft b^9 , and held in a central position, as herein shown, by a spring b^{10} , acting on a post b^{12} , secured to the plate a . The arms of the yoke b^7 have secured to them contact arms or springs $b^{13} b^{14}$, which co-operate with contact-points (shown as screws $b^{15} b^{16}$) adjustable in the upright posts $a^{18} a^{19}$. The ratchet-wheel a^6 is rotated in opposite directions by the magnets $a' a^2$ attracting their armatures, as will be described, and is held fixed or stationary, when the said armatures are unattracted, by a pawl b^{20} , acted upon by a spring b^{22} , (see Fig. 2,) the said pawl assisting to complete the movement of the ratchet-wheel the distance of one tooth, as will be described.

45 The transmitting-instrument has connected to it, as will be described, one or more receiving-instruments, each provided with magnets $c c'$, supported by a base-plate c^2 , having secured to it a suitable clock mechanism, 50 only one gear-wheel c^3 of which is shown in Fig. 6, the said clock-work being of any usual or well-known construction and having its gears regulated to revolve a recording-dial c^4 , secured to the arbor c^5 , as by thumb-nut c^6 , once in twenty-four hours, or it may be any other desired duration of time in which a record is to be made. The magnets $c c'$ are provided with armatures $c^7 c^8$, fastened to or forming part of a yoke c^9 , which is itself secured to or forms part of a pallet-bar c^{10} , provided with pallets $c^{12} c^{13}$, substantially as shown in connection with the transmitting-instrument. The pallets $c^{12} c^{13}$ actuate a ratchet-wheel c^{14} on a shaft c^{15} , provided with a pinion c^{16} , which meshes with a gear-wheel c^{19} , meshing with the segmental arm c^{20} , mounted on a shaft c^{21} , having bearings in an

arm c^{22} , supported by the plate c^2 and extended therefrom beyond the graduated ring c^{23} , the latter being shown plain or unmarked 70 in Fig. 5. The ratchet-wheel c^{14} is similar in construction to the wheel a^6 , it being provided with teeth, each having its sides oppositely inclined at substantially the same angle, so that the said wheel may be rotated in opposite directions. The ratchet-wheel c^{14} is held stationary when not engaged by the pallets $c^{12} c^{13}$ by a pawl c^{20} , held in engagement with the said ratchet-wheel by a spring c^{21} , the said spring-actuated pawl assisting to rotate the 80 said ratchet-wheel one step or tooth. The shaft c^{21} has mounted upon it above the graduated ring c^{23} an arm c^{24} , carrying a pen or other indicating or recording device, (not shown,) by which a permanent record may be 85 made upon the graduated dial c^4 in usual manner.

The recording-instrument in practice will be contained in a suitable casing or box. (Not shown.)

90 The receiving-instrument, as shown in Fig. 5, is provided with four connecting-plates 8, 9, 10, and 12, the plate 9 being in electrical connection with the base-plate c^2 of the instrument and the remaining plates insulated 95 from said base-plate. The plate 8 is connected to the magnet c and the plate 12 to the magnet c' , and both magnets are electrically connected, as by wire 50, through the base-plate c^2 with the connecting-plate 9, while the plate 10 is connected, as by wire d^x , to the post d , insulated from the base-plate c , supporting one member d' of a circuit-closer, the co-operating member d^2 of which is shown as a bar or arm which is mounted on a pivoted shaft d^3 , (see Fig. 7,) supported by the base-plate c^2 , and the bar d^6 , supported above the said base-plate, the said arm being normally brought by gravity in contact with the member d' . The contact member d^2 is raised out of contact with the member d' by a circuit-breaker, shown as a bar d^4 , secured to a shaft d^5 , having bearings in the base-plate c^2 , and a thin bar d^6 . The bar d^4 is extended across the pallets $c^{12} c^{13}$, and is bent in opposite directions 115 to form arms $d^7 d^8$, with which co-operate studs $d^9 d^{10}$, carried by the pallets $c^{12} c^{13}$, respectively, the arm d^7 being prolonged, as shown in Fig. 7, to engage a screw or stud d^{12} , carried by the arm d^2 , the said arm being normally held in engagement with the stud d^{12} , when the pallets are out of engagement with the teeth of the wheel c^{14} , by a spring d^{13} , having one end secured to the said arm and its opposite end fastened to a post d^{14} , secured to the plate c^2 . The arms $d^7 d^8$ of the bar d^4 extend in opposite directions, and the studs $d^9 d^{10}$ are located on opposite sides of the said bar, so that when the yoke c^9 is moved in one direction, as by the magnet c , the stud d^{10} will 120 ride up the inclined arm d^8 and bring the arm d^7 in engagement with the stud d^{12} and lift the bar d^2 from the contact member d' , and also when the yoke is moved by the magnet 125 130

c' the stud d³ will act upon the arm d⁷ and move it in the same direction to lift the bar d² out of engagement with the contact member d'. It will thus be seen that when either 5 magnet is energized the circuit-breaker is rendered operative. Referring to Fig. 8, the bed-plate of the transmitter is connected by a wire e to one pole of the battery e', and the post d of one of the receiving-instruments is 10 connected to the other pole of the battery by the wire e².

The post 6 of the transmitting-instrument is connected by wire e³ to the magnet c of the receiving-instrument, and the post 7 by the 15 wire e⁴ to the magnet c' of the receiving-instrument, and the magnets a' a² of the transmitting-instrument are connected by wires e⁵ e⁶ to a common wire e⁷, connected to the base-plate of the receiving-instrument.

20 In the operation of my improved telemeter system the pointer e⁸ of the receiving-instrument and the pointer e⁹ of the transmitting-instrument are first adjusted to indicate the same temperature—namely, the normal temperature 25 of the locality in which the transmitting-instrument is situated and the variations from which it is desired to register on the receiving-instrument. In case the temperature falls below or rises above the normal in the locality in which the transmitting-instrument is located, the pointer e⁸ will be moved by the thermometer A' into contact with one or the other of the contact-points a¹⁶ a¹⁷ on the arms a¹⁴ a¹⁵, thus energizing one or 30 the other of the magnets a' a², and through the armatures of the said magnets energizing the magnets c c' of the receiving-instrument, thereby causing the arm c²⁴ to be moved over the graduated dial c⁴ and leave thereon a permanent record of the variations from the normal at the transmitting-instrument.

Referring to Fig. 8, let it be supposed that the pointer a³ is brought in contact with the contact member a¹⁶. In this instance the circuit 45 through the magnet a' is closed, which circuit may be traced as follows: from the positive pole of the battery by wire e to the pointer a³, thence the arm a¹⁴, wire a²² to post a²³, and wire a²⁴ to the magnet a', and from the 50 magnet a' by wires e⁵ e⁷ and base-plate c² of the receiving-instrument to the contact-arm d², and thence through the contact member d' and wire e² to the battery. As soon as the magnet a' is energized it first attracts the 55 winker-armature b⁵, which completes a shunt-circuit around the contact-point a¹⁶, the shunt-circuit being completed through the magnet a'. As soon as the pointer completes the circuit of the magnet through the contact-point 60 a¹⁶ a light current passes through the said magnet, energizing it sufficiently to attract the winker-armature, while the armature b' remains at rest. As soon as the shunt-circuit is completed by the winker-armature a 65 stronger current passes through the magnet by means of stronger contact at the arm b¹⁸ and the armature b' is attracted, bringing the

spring 2 in contact with the post 6, thus dividing the current from the battery, so that a part passes to the line e⁷ through the magnet a', while the remaining portion passes to the line from the base-plate through the yoke b and spring 2. The divided circuit around the magnet a' may be traced as follows: from the battery e' by wire e to the bed-plate, thence 70 by the yoke b, arm 2, and post 6, and wire e³ to the magnet c of the receiver, through the bed-plate, the arm d², contact member d', and wire e² to the battery. As the magnet c of the receiver is energized, its armature c⁷ is 75 attracted and the pallet c¹² rotates the ratchet-wheel c¹⁴ one step, thereby moving the recording-arm c²⁴ by means of the segmental gear c²⁰, thus leaving a permanent record on the graduated dial c⁴. As the pallet c¹² rotates the ratchet-wheel c¹⁴, the bar d⁴ is moved, 80 as described, to lift the contact member d² from the contact member d', and thus break the circuit through the transmitter, permitting the armature b' and winker-armature b⁵ 85 to be restored to their normal positions, as shown by a spring, such as b¹⁰. If the pointer a³ is brought into engagement with the contact-point a¹⁷, the magnet a² is energized in a similar manner and the circuit of the magnet 90 c' completed by the arm 3 and post 7, and the shunt around the contact-point a¹⁷ completed through the arm b¹⁴ and post a¹⁹, the armature c⁸ being thus attracted and the ratchet-wheel c¹⁴ moved in the opposite direction by the 95 pallet c¹⁸, thus moving the arm c²⁴ in the opposite direction from that in which it was moved by the pallet c¹², leaving a permanent record on the dial with the variation in the 100 opposite direction.

In Fig. 8 I have shown two receiving-instruments connected to the transmitting-instrument and the circuit-breaker located at the most remote receiving-instrument; but instead thereof any desired number of receiving-instruments may be connected to the transmitting-instrument, there being a single receiving-instrument shown in Fig. 9. So, also, the circuit-breaker may be connected to any one of the receiving-instruments. I prefer to employ the arrangement of circuits shown in Figs. 8 and 9; but instead thereof I may employ the arrangement of circuits shown in Fig. 10, wherein the magnets a' a² of the transmitting-instrument are respectively connected by wires m m' to the magnets c c' of the receiving-instrument. One pole of the battery e', as the positive pole, is connected to the base-plate of the transmitting-instrument by wire e. The arm d⁴, operated by the pallet-bar a⁹, forms one member of a circuit-closer in the arrangement of circuits shown in Fig. 10, the co-operating member m³ of which is connected by wire m⁴ to an electro-magnet m⁵, also connected by 110 wire m⁶ with the positive wire e. The negative pole of the battery is connected by the wire e² to the post d, to which is secured the member d' of the circuit-closer, the co-oper- 115 120 125 130

ating member d^2 of which is shown as an elbow-lever pivoted as at m^7 and having its arm m^8 in position to be acted upon by the armature m^9 of the electro-magnet m^5 .

- 5 With the arrangement shown in Fig. 10 the circuit of the battery is first closed at one of the contact-points—as, for instance, the contact-point a^{16} —and the circuit completed through the magnet a' , the said circuit being 10 traced as follows, viz: from the positive pole of the battery by wire e , pointer a^3 , contact-point a^{16} , bar a^{14} , wires a^{22} a^{24} , through the magnet a' , thence by wire m to magnet c , through the magnet c to the bed-plate c^2 of 15 the receiving-instrument, thence by wire d^x , circuit-closer d^2 d' , and wire e^2 to the negative pole of the battery. As soon as the circuit is completed through the magnet a' the shunt-circuit around the contact-point a^{16} is 20 completed through the magnet a' by the arm b^{13} and post a^{23} , and on the passage of the current through the magnet c the pallet-bar c^{10} brings the bar d^4 in contact with the member m^8 , thus closing the circuit of the electro-magnet m^5 , which is located in a shunt-circuit around the battery. The magnetizing of 25 the magnet m^5 attracts its armature m^9 , and the latter strikes the arm m^8 of the circuit-closing lever d^2 and turns said lever on its pivot 30 and lifts it out of contact with the member d' , thus breaking the battery-circuit after the record has been made on the receiving-instrument. It will be noticed that the circuit-breaker acts as a centering device by which 35 the pallets c^{12} c^{13} are brought to their central or normal position as soon as the circuit is broken, thus bringing the armatures of the magnets equal distances from the poles of the said magnets and insuring the operation 40 of the receiving-instrument. The centering device for the transmitter is shown in Fig. 2 as two springs m^{20} m^{21} , acting on a stud m^{22} .

I have herein described my improved apparatus as employed for recording variations in temperature; but I do not desire to limit my invention to this particular use, as it may be employed equally as well to indicate other phenomena.

I claim—

- 5c 1. The combination, with a battery, of a transmitting apparatus provided with a pointer to automatically complete the battery-circuit and also provided with an electro-magnet in circuit with said battery, a shunt-circuit through said magnet and around said 55 circuit-closing pointer, a second or divided circuit around said magnet, a receiving apparatus having an electro-magnet placed in said divided circuit and which constitutes 60 both a receiving-magnet and a circuit-breaking magnet as well, recording mechanism controlled by movement of the armature of said receiving and circuit-breaking magnet, and a circuit-breaker also operated by movement 65 of said armature to break the battery-circuit, substantially as described.

2. The combination, with a battery, of a transmitting apparatus having a pointer connected to said battery, two contact-points, electro-magnets connected to said contact-points, armatures of said magnets connected together to move simultaneously in opposite directions with relation to their respective magnets, a shunt-circuit around said contact-points, completed by the attraction of the 70 armature of the magnets, and a receiving-instrument having electro-magnets in the said shunt-circuits, and armatures for said magnets connected together to move simultaneously in opposite directions, a toothed surface, and a pallet-bar connected to said armatures and provided with pallets to engage said toothed surface, substantially as described. 80

3. In an electrical instrument, the combination, with two magnets, of armatures for 85 said magnets, connected together to move simultaneously in opposite directions with relation to their respective magnets, a ratchet-wheel having the sides of its teeth oppositely inclined at substantially the same angle, a 90 pallet-bar connected to said armatures and provided with pallets normally disengaged from said ratchet-wheel and a spring-actuated pawl to assist in moving the ratchet-wheel, and a centering-device to restore the 95 pallet-bar to its normal position with its pallets disengaged from the ratchet-wheel when the circuit of the operating-magnet is broken, substantially as described.

4. In an electrical instrument, the combination, with two magnets, of armatures for 100 said magnets, connected together to move simultaneously in opposite directions with relation to their respective magnets, and auxiliary or winker armatures for said magnets, 105 connected together to move simultaneously in opposite directions, substantially as and for the purpose specified.

5. In an electrical instrument, the combination, with two magnets, of armatures for 110 said magnets, connected together to move simultaneously in opposite directions with relation to their respective magnets, a pallet-bar provided with pawls, and a bar, as d^4 , connected to the said pawls, whereby one arm or 115 end of the said bar is moved positively in the same direction on the movement of the pallet-bar in either direction, substantially as described.

6. The combination, with an electrical receiving-instrument provided with electro-magnets and a pointer and an indicating ring or dial and a clock mechanism to move said pointer, of a recording-dial located in front of the receiving-instrument within the indicating-ring, a recording-instrument, the arm c^{24} , to which the recording-instrument is connected, and a segmental gear connected to said arm and actuated by the said electro-magnets to move said recording-instrument over the 125 said dial, substantially as described. 130

7. The combination, with a pallet-bar hav-

ing pawls, of a centering device therefor, consisting of the bar d^4 , having arms to engage said pawls, substantially as described.

8. The combination, with a battery, of a transmitting apparatus having a pointer connected to said battery, two contact-points, electro-magnets connected to said contact-points, main armatures for said magnets, connected together to move simultaneously in opposite directions, and winker-armatures for said magnets, connected together to move simultaneously in opposite directions, a shunt-circuit around said contact-points, completed by the winker-armatures, and a divided circuit completed by the attraction of the main armatures of the said magnets, and a receiv-

ing-instrument having electro-magnets in the shunt or divided circuits, armatures for said magnets, connected together to move simultaneously in opposite directions, a toothed surface, and a pallet-bar connected to said armatures and provided with pallets to engage said toothed surface, substantially as described.

In testimony whereof I have signed my name to this specification in the presence of two subscribing witnesses.

FERNANDO J. DIBBLE.
